Primary Examiner — Vy N Koenig(74) *Attorney, Agent, or Firm* — Gerard J. McGowan, Jr.(57) **CLAIM**

The ornamental design for a black box, as shown and described.

DESCRIPTION

FIG. 1 is a perspective view of a black box showing our new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top plan view thereof; and,

FIG. 7 is a bottom plan view thereof.

The broken lines are directed to environment only and form no part of the claimed design.

1 Claim, 5 Drawing Sheets(56)
